UNITED STATES PATENT OFFICE.

MANUEL BLICKMAN, OF NEW YORK, N. Y.

DESIGN FOR A STERILIZER.

58,540.

Specification for Design.

Patented Aug. 2, 1921.

Application filed November 10, 1919. Serial No. 337,027. Term of patent 14 years.

To all whom it may concern:

Be it known that I, MANUEL BLICKMAN, a citizen of the United States, residing at New York city, in the county of New York and State of New York, have invented a new, original, and ornamental Design for Sterilizers, of which the following is a specification, reference being had to the accompanying drawing, forming part of the same.

Figure 1, is an end view of a sterilizer chamber showing my new design, and Fig.

2, is a side view of the same, the door at each end being shown as closed.

By means of dotted lines at the bottom of the central band, I have indicated a downwardly projecting part, which may be the connection with the source of supply of the sterilizing gas or vapor.

I claim:—

The ornamental design for a sterilizer, as shown and described.

MANUEL BLICKMAN.
